UNITED STATES PATENT OFFICE.

PETER SHIMER CRISWELL, OF WHEELING, WEST VIRGINIA.

WAGON-BRAKE.

SPECIFICATION forming part of Letters Patent No. 437,916, dated October 7, 1890.

Application filed June 20, 1890. Serial No. 356,101. (No model.)

To all whom it may concern:

Be it known that I, PETER SHIMER CRISWELL, a citizen of the United States, residing at Wheeling, in the county of Ohio and State 5 of West Virginia, have invented certain new and useful Improvements in Wagon-Brakes; and I do hereby declare the following to be a full, clear, and exact description of the invention, such as will enable others skilled in 10 the art to which it appertains to make and use the same.

The invention relates to that class of wagon-brakes in which the wagon-body slides forward by gravity when the vehicle is on a declivity, so as to put on the brakes.

The invention will first be described in connection with the drawings, and then pointed out in the claim.

Figure 1 of the drawings is a bottom plan 20 view of a wagon with my brake; Fig. 2, a longitudinal vertical section through the middle, and Fig. 3 a detail vertical section.

In the drawings, A represents the bottom 25 of the wagon-body, to which is attached the front cross-piece B, the rear cross-piece C, the cross-bar D, and the bearings E E.

On the front cross-piece B is fastened at its middle the trough $b b$, in which are journaled the friction-rolls b' , which extend below the 30 trough sides $b^2 b^2$. On the rear cross-piece are arranged two similar troughs $c c$, carrying rolls $c' c'$, one on each side. These roller-troughs are overlapped by troughs $b^3 c^3 c^3$, attached to the under side of the vehicle-springs F, the rollers $b' c'$ bearing upon the 35 bottom of the troughs $b^3 c^3$. The rear axle and front bolster being attached to the springs, the body of the wagon will on a decline slide for-

ward, being limited in extent by the rear closed ends $b^4 c^4$. It is this movement which 40 I employ to put on the brakes.

In the bearings E E, I arrange the rotary or oscillating shaft G, which has the four crank-arms $g g$ and $g' g'$, the former being provided with horizontal ends, which carry 45 the brake-shoes H H, while the latter $g' g'$ have their ends connected by a rope or chain with the cross-bar D on the bottom of the wagon-body. The flexible connection D' passes intermediately over pulleys rotating 50 on the frames I I, attached to the rear axle J. These pulleys K K do not run in a plane parallel to the longitudinal axial line of the vehicle, but obliquely thereto, so that the ropes may not contact with the springs. As the 55 body of the wagon moves forward, the crank-shaft is turned so as to put the brakes on the wheels, while as soon as a level or upward incline is reached the running-gear is pulled forward under the weight of the wagon-body, 60 so as to take the brakes off the wheels.

What I claim as new, and desire to protect by Letters Patent, is—

In a wagon-brake, the arms $g' g'$, connected with the bottom of the wagon-body by ropes 65 passing over pulleys on the axle, combined fixedly with a crank-shaft G, which is journaled on the bottom of said body, as and for the purpose set forth.

In testimony whereof I affix my signature in 70 presence of two witnesses.

PETER SHIMER CRISWELL.
